UNITED STATES PATENT OFFICE.

FRANK H. MASOW, OF BERKELEY, CALIFORNIA.

SAW-FILING DEVICE.

Application filed June 1, 1921. Serial No. 474,074.

To all whom it may concern:

Be it known that I, FRANK H. MASOW, a citizen of the United States, residing at Berkeley, in the county of Alameda and State of California, have invented new and useful Improvements in Saw-Filing Devices, of which the following is a specification.

This invention relates to filing devices, and particularly to that class employed for 10 filing saws other than circular.

One of the objects of the present invention is to generally improve and simplify devices of the character described, and especially to provide a compact portable saw 15 filing device which may be efficiently employed by any ordinary mechanic without previous instructions or skill, and which is adapted to be folded into a compact unit for storage in a tool box or the like.

Another object of the invention is to provide a saw filing device which may be readily attached to a work bench or any other suitable support, and which is provided with clamping means for receiving, 25 positioning and rigidly securing the saw to be filed.

Another object of the invention is to provide a file supporting and guiding frame, and in conjunction therewith means permitting vertical and angular adjustment of 30 the frame and longitudinal movement thereof with relation to the saw.

Further objects will hereinafter appear.

The invention consists of the parts and 35 the construction, combination and arrangement of parts as hereinafter more fully described and claimed, having reference to the accompanying drawings, in which—

Fig. 1 is a plan view of the saw filing 40 device.

Fig. 2 is an end view.

Fig. 3 is an end view of the file clamp and adjusting mechanism.

Fig. 4 is an enlarged detail plan view of 45 the sliding support, and the means whereby angular adjustment of the file on a horizontal plane with relation to the saw is obtained.

Referring to the drawings in detail, and 50 particularly to Figs. 1 and 2, there is shown a frame consisting of two main clamping sections, such as indicated at 2 and 3. Formed on each end of the clamping section 3 is an upwardly extending bracket 4, and similarly formed on each end of the clamping section 2 is an upwardly extend-

ing bracket 5. The bracket sections 4 and 5 are pivotally connected at each end as shown at 6 and a clamping screw actuated by a thumb nut 7 also passes through the brackets to draw the same, together with the clamping sections 2 and 3, together when a saw, such as shown at 8, is placed between the same. Also formed on each end of the clamping section 3 is a downwardly 60 extending bracket 9, and secured thereby in any suitable manner is a guide rod 10 on which is slidably mounted a plate 11. The plate 11 consists of a single sheet of metal bent about the square rod as shown in Fig. 70 1, to form an upper section 11 and a lower section 11^a. These sections are substantially semi-circular in shape and they are interspaced to receive a guide arm 12. The arm 12 is pivotally mounted between the plate 75 sections 11 and 11^a as at 13, and an extreme swinging movement of the arm is limited by a pair of stop members 14. The plates as previously stated are slidably mounted on the guide rod 10, but they are secured 80 against lateral movement with relation thereto by means of a pair of pins as shown at 15; the pins being secured between the plates. The upper surface of the plate 11 is graduated as at 16 to indicate the angular position of the arm 12, and the arm 85 may be secured at any intermediate point between the stops 14, or when in engagement with the stops by means of a clamping screw 17. Slidably mounted on the 90 guide arm 12 is a frame 18. One end of the frame fits the arm 12 and only has a sliding movement thereon as shown at 19, while the opposite end of the frame has a limited vertical movement with relation to 95 the guide arm 12 by elongating the slot indicated at 20, thereby permitting the frame to rock as well as slide on the arm 12. The file proper shown at 21 is secured in 100 the usual manner to a handle 22. This handle however is clamped to the frame by passing it through a rear socket member 23 and by securing it in a clamp mounted on the forward end of the sliding frame as at 24. This clamp consists of two arms 25 and 26 hingedly connected as at 27. A clamping screw actuated by a thumb nut 28 passes through the arms and thereby permits them to be tightly drawn together to 105 engage the shank of the file. The file however may be turned within the clamp to assume any angular position desired with 110

relation to the teeth on the saw, and such angular adjustment is indicated by a triangular pointer 29 and a graduated dial plate 30.

- 5 The main clamp A, consisting of the sections 2, 3, etc., is so constructed that it may be readily and quickly attached to a work bench or any other suitable support, that is the clamping section 2 is provided with a 10 horizontally disposed supporting flange 31, adapted to engage the top of a bench, and the forward face of the clamping section is provided with one or more prongs 32 to enter the front face of the bench. Similarly 15 one or more prongs such as shown at 33 may be provided which may be driven into the upper surface, thus rigidly securing the clamp with relation to the bench or otherwise.
- 20 The saw to be filed and as indicated at 8 is inserted between the clamping sections 2 and 3 by first loosening the wing nuts 7. This permits sufficient separation of the clamping sections to permit the saw to be 25 entered between the same. The saw is then lifted in a vertical direction until the teeth engage a pair of aligning ferrules 34 constructed of lead or the like, and which are supported by the clamping screws carrying 30 the wing nuts 7. The saw when in engagement with these ferrules is stopped against further upward movement and will when so engaging the ferrules insure correct positioning of the saw between the clamping 35 sections, which may then be brought together by tightening the wing nuts. A file such as shown at 21 is next inserted between the clamping sections 23 and 24 and adjusted by means of the clamping sections 25 and 40 26 to present the desired angle with relation to the teeth. Angular adjustment of the arm 12 is also obtained to give the teeth the desired rake and when this adjustment is secured, arm 12 is locked by means of the 45 clamping screw 17. The file may now be grasped by the handle 22 and pulled across the face of the teeth; the file engaging the teeth when the handle is moved in one direction, and being lifted away from the teeth 50 when moved in the other direction; lifting of the file or freeing the same with relation to the teeth during retracting movement being permitted due to the fact that the slot 55 20 is elongated as shown. Each tooth is filed until the desired depth is obtained and the file is advanced from tooth to tooth by sliding the plates 11 and 11^a longitudinally on the rod 10. The plates 11 and 11^a automatically grip the guide rod 10 when a certain tooth is being filed as the downward pressure exerted on the file when filing also exerts a pressure on the guide arm 12. This arm of course tends to tilt the plates 11 and 11^a with relation to the guide rod 10, and

the plates therefore grip the rod and are thereby held against longitudinal movement while a certain tooth is being filed. However the moment pressure is released, it is obvious that sliding movement can be readily imparted to the plates or the saw filing frame as a whole when the next tooth is to be filed.

From the foregoing description it can be seen that I have provided an exceedingly compact and simple saw filing device. First the device as a whole may be quickly attached to a work bench or any other suitable support; secondly, insertion and clamping of the saw and correct positioning of the same is also easily accomplished; third, angular adjustment both in a vertical direction and in a horizontal direction with relation to the saw is permitted, and longitudinal movement of the saw filing frame can be obtained whenever the file is shifted from one tooth to another; fourth, a uniform pitch and rake is easily obtained by any ordinary mechanic without previous instructions or skill as once the right adjustment has been obtained, each tooth will be filed to the same identical angle; the only care required during the filing operation being that no tooth is filed too deep. The saw can be filed from one side until completed and it may then be removed and reversed, thus permitting both sides to be filed to an identical angle, both in a horizontal and in a vertical direction; uniformity and efficient cutting qualities being thus obtained.

If it is desired to change the angle or rake of the teeth, it is accomplished by merely releasing the clamping screw 17 and swinging the guide arm to any angle desired; similarly angular adjustment of the file with relation to the teeth may be obtained by adjustment of the screw 28. Therefore, any result desired may, practically speaking, be obtained.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand.

Having thus described my invention, what I claim and desire to secure by Letters Patent is—

1. In a device of the character described, a clamping member for the reception of a saw, a guide rod secured to the said clamping member, an arm longitudinally movable freely on said rod, and a file supporting frame mounted for a free slidable and also a free rocking movement on the arm.

2. In a device of the character described a clamping member for the reception of a saw, a guide rod secured to said clamping member, an arm longitudinally movable on said rod, a file supporting frame slidable on the arm, and means permitting vertical movement of one end of the file supporting frame with relation to the arm. 5
3. In a device of the character described, a clamping member for the reception of a saw, a guide rod secured to the said clamping member, a relatively long arm longitudinally movable on said rod, a file supporting frame mounted for a free sliding and a free 10 rocking movement on the arm during the sharpening operation, and means for permitting turning movement or angular adjustment of the file with relation to the frame. 15
4. In a device of the character described a clamping member for the reception of a saw, a guide rod secured to said clamping member, an arm longitudinally movable on said rod, a file supporting frame slidable on the arm, means permitting horizontal angular adjustment of the arm with relation to the rod, means permitting vertical movement of one end of the frame with relation to the rod, and means permitting angular adjustment of the file with relation to the frame. 20
5. In a device of the character described the combination with a saw clamping means and a guide rod supported thereby, of a pair of connected plates slidably mounted on the 25
- rod, an arm pivotally mounted between the plates, means permitting horizontal angular adjustment of the arm between the plates, and means for securing the arm when adjusted. 30
6. In a device of the character described the combination with a saw clamping means and a guide rod supported thereby, of a pair of connected plates slidably mounted on the rod, an arm pivotally mounted between the plates, means permitting horizontal angular adjustment of the arm between the plates, means for securing the arm when adjusted, a file supporting frame slidably mounted on the rod, means for securing a file therein, and means permitting turning movement of the file to adjust its angular position with relation to the saw. 35
7. In a device of the character described the combination with a saw clamping means and a guide rod supported thereby, of a pair of connected plates slidably mounted on the rod, an arm pivotally mounted between the plates, means permitting horizontal angular adjustment of the arm between the plates, means for securing the arm when adjusted, a file supporting frame slidably mounted on the rod, means for securing a file therein, means permitting turning movement of the file to adjust its angular position with relation to the saw, and means permitting vertical movement of one end of the file supporting frame with relation to the arm. 40
